(57) **CLAIM**

The ornamental design for a golf glove and hook-and-loop attachment strap, as shown and described.

DESCRIPTION

FIG. 1 is a front elevation view of a golf glove and hook-and-loop attachment strap showing my new design with the strap shown broken away for clarity of illustration.

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top, front perspective view shown on a reduced scale showing the golf glove in condition of use on a hand and the hook-and-loop attachment strap on a golf club thereof.

The broken lines showing of an arm and golf club in FIG. 7 are for illustrative purposes only and form no part of the claimed design.
